UNITED STATES PATENT OFFICE

CARL G. PRITCHARD, OF HIRAM, OHIO, ASSIGNOR TO HARRIS-SEYBOLD-POTTER COMPANY, OF CLEVELAND, OHIO, A CORPORATION OF DELAWARE

PRINTING PRESS

Application filed October 31, 1930. Serial No. 492,391.

My invention relates to rotary printing-
presses particularly of the gravure type em-
ploying cylinders etched by photo-mechanical
processes, and especially to the means for
5 tensioning or clamping the tubular copper
plate or shell that is slipped over the plate-
cylinder forming the printing couple with
the impression-cylinder.

Heretofore the common practice has been
10 until recently in using rotogravure plate-cyl-
inders to have the cylinder carry a heavy
copper shell on its periphery, which shell is
successively ground down after each job to
receive a fresh design. After the cylinder
15 becomes of too small diameter for the press,
it must be removed from the press and a new
shell built up on the cylinder to the proper
original diameter.

According to recent methods a thin copper
20 shell is deposited on a cast-iron core or man-
dril by electroplating, which shell is then
slipped off the core and placed on the plate
cylinder of the press, the object being to have
this shell used for only one design and then
25 replaced by a similar shell for the next job.

The object of my invention is, among other
things, the provision of novel and simplified
means for clamping and firmly holding such
30 tubular shells slipped over the plate-cylinder
so that such shell will not slip or creep on
the cylinder during the printing process.

In a sheet-fed press such means are lo-
cated in the plate-cylinder opposite the usual
35 opening in the impression-cylinder so that
no printing pressure is exerted from the im-
pression-cylinder on the shell adjacent such
tensioning means when the press is printing
the successive sheets.

With these and other objects in view, the
40 invention comprises certain constructions
hereinafter described and then particularly
pointed out in the claims, and a preferred
embodiment of my invention is illustrated in
the accompanying drawings in which—

45 Fig. 1 is a side elevation of a printing
couple embodying my invention, the plate-
cylinder being partly cut away to show some
of the parts in vertical section;

50 Fig. 2 is an end view of the plate-cylinder
partly in section on the line 2—2 of Fig. 1;

Fig. 3 is a top plan view of the plate-cyl-
inder showing the shell tensioning devices in
removable position;

Fig. 4 is a modified form of the tension
block shown in side elevation as in Fig. 1;

Fig. 5 is an end view of the tubular shell
with a reinforcing strip attached to the shell
to be used in the modified construction of
Fig. 4;

Fig. 6 is an enlarged section on the line 60
6—6 of Fig. 5; and

Fig. 7 is a top plan view of the plate-
cylinder shown in Fig. 4.

Similar numerals refer to similar parts
throughout the several figures.

Referring to Figs. 1, 2 and 3, the impres-
sion-cylinder 8 coacts with the plate-cylinder
9 to form a printing couple, the cylinder 8
having the cut-out portion 10 within which
are arranged the cylinder grippers 11 to 70
carry the sheet 12 into the bite of the cyl-
inders 8 and 9 in the usual way. The plate-
cylinder 9 is longitudinally slotted or
grooved at 13 opposite the cut-out portion
10 to receive the collapsible segment 14 which
15 is used to tension the tubular copper shell
slipped over the plate-cylinder 9.

The segment 14 comprises the base plate
16 carrying a plurality of upright pins 17
at each end of the plate 16, the pins 17 act-
ing to position a like number of heavy coil-
springs 18 seated in corresponding recesses
formed in the upper block 19 extending lon-
gitudinally through the slot 13 in the cyl-
inder 9. The block 19 has the outwardly pro-
jecting lugs 20 formed along its inner lower
edges so shaped to engage the inner abut-
ments 21 of the cylinder 9 when the curved
top 22 of the block 19 is flush with the cir-
cumference of the cylinder 9 as shown in 90
Fig. 1.

Means are provided for compressing and
locking the segment 14 below the chord of
the arc of the cylinder 9 so that the shell
15 may be slipped over the end of the cyl-
inder 9 and be positioned thereon: In the
embodiment shown, the end members 23 ar-
ranged at the ends of the block 19 have suit-
able holes 24 bored therein to be engaged by 100
pins 25 passing through holes 26 in the levers

- 27 removably pivoted to the cylinder 9 by the screw-studs 28. The end of each lever 27 is connected by the detachable link 29 to the locking rock-arm 30 pinned to the cylinder 9 by the stud 31. The rock-arm 30 carries the lug 32 recessed at 33 to be engaged by the removable locking-bar 34 to throw the rock-arm 30 over center at 31 as indicated by dotted lines in Fig. 1.
- 10 When the block 19 is so depressed or collapsed with coil springs 18 compressed, the shell 15 is positioned on the plate cylinder 9, and thereafter the block 19 is released to rise radially in the groove 13 to normal position (Fig. 1) to tighten or tension the shell 15 to make a true cylinder, the shell 15 being made very slightly smaller in diameter so as to be put under tension by the spring-pressed block 19. The outer peripheral surface of the top 22 of the block 19 may be slightly roughened, if desired, in order to bite into the inner surface of the shell 15 and so prevent the latter from shifting its position on the cylinder 9. The block 19 is not subjected to printing pressure because of the oppositely-disposed cut-out portion 10 in the cylinder 8, and so the uniform pressure exerted by the springs 18 is not disturbed in the printing operation. Fig. 3 shows how the compressing and locking means for the segment 14 at either end of the cylinder 9 (Fig. 2) may be released so that such segment may be shifted and positioned within the grooved slot 13 before the shell 15 is slipped over the cylinder 9.
- 15 Referring to the modified form of Figs. 4-7, the depressible block 19 has its top 22 formed with a longitudinal groove 35 to receive the longitudinal reinforcing strip 36 affixed to the inner surface of the shell 15 as shown in Figs. 5 and 6. The mechanism for compressing and locking the block 19 is the same as that already described herein in the Figs. 1-3 construction.

- Changes and variations may be made in the constructions shown and described without departing from the principles of the invention or sacrificing its chief advantages; hence such invention is not to be confined to

the structures shown in the accompanying drawings.

I claim as my invention:—

1. In combination, a printing cylinder, a tubular plate fitted over said cylinder and spring-pressed, radially movable means within the cylinder to tension the plate thereon. 70
2. In combination, a printing cylinder having a gap, a tubular plate fitted over said cylinder and spring-pressed, radially movable means within the cylinder gap to tension the plate thereon. 75
3. In combination, a printing cylinder, a tubular plate fitted over said cylinder, spring-pressed, radially expansible means within the cylinder normally tensioning the plate thereon, and means to move said means inwardly within the cylinder while compressing said spring to permit positioning of the 80 tubular plate on the cylinder.
4. In combination, a printing cylinder, a tubular plate fitted over said cylinder, spring-pressed, radially expansible means within the cylinder normally tensioning the plate thereon, and means to move and lock 90 said means inwardly within the cylinder while compressing said spring to permit positioning of the tubular plate on the cylinder. 95
5. In combination, a printing cylinder, a tubular plate fitted over said cylinder, spring-pressed, radially expansible means within the cylinder normally tensioning the plate thereon, and detachable means to move 100 and lock said means inwardly within the cylinder while compressing said spring to permit positioning of the tubular plate on the cylinder. 105
6. In combination, a printing cylinder having a gap, a cylindrical plate shell fitted peripherally on said cylinder, expansible means within the cylinder gap normally tensioning and holding the plate shell in position, and means to compress said spring and move said expansible means within the cylinder gap to permit positioning of the plate shell on the cylinder. 110
7. In a rotary printing-press, an impression cylinder and a printing cylinder both 115 cylinders having coincident gaps to comprise a printing couple, a tubular plate fitted over the printing cylinder, and spring-pressed, radially expansible means within the printing cylinder gap opposite the impression cylinder to tension the plate on its cylinder out of contact with the impression cylinder. 120
8. In a rotary printing-press, an impression cylinder and a printing cylinder both 125 cylinders having coincident gaps to comprise a printing couple, a tubular plate fitted over the printing cylinder, and spring-pressed, radially expansible means within the printing cylinder gap opposite the impression cylinder to tension the plate on its cylinder. 130

out of contact with the impression cylinder.

9. In combination, a printing cylinder, a tubular plate fitted over said cylinder, means longitudinally projecting along the inner 5 surface of said plate and engaging said cylinder to hold the plate in fixed relation with said cylinder, and means bearing on said strip to tension the plate on the cylinder.

10. In combination, a printing cylinder, a 10 tubular plate fitted over said cylinder, means longitudinally projecting along the inner surface of said plate and engaging a longitudinal groove on the periphery of said cylinder to hold the plate in fixed relation with 15 said cylinder, and means bearing on said strip to tension the plate on the cylinder.

11. In combination, a printing cylinder having a gap, a tubular plate having a longitudinal strip on its inner surface fitted over 20 said cylinder, and radially movable means having its outer surface grooved to contain said strip carried within the cylinder gap to tension the plate on the cylinder.

12. In combination, a printing cylinder 25 having a gap, a tubular plate having a longitudinal strip on its inner surface fitted over said cylinder, and spring-pressed, radially movable means having its outer surface grooved to contain said strip carried within 30 the cylinder gap to tension the plate on the cylinder.

13. In combination, a printing cylinder, a tubular plate fitted over said cylinder, spring-pressed, radially expansible means 35 within the cylinder to tension the plate thereon, and means to limit the outward radial movement of said means bearing on said plate.

CARL G. PRITCHARD.
